Primary Examiner — Cynthia Ramirez*Assistant Examiner* — Tamara L Hahn(74) *Attorney, Agent, or Firm* — Bay State IP, LLC(57) **CLAIM**

The ornamental design for a trash receptacle, as shown and described.

DESCRIPTION

FIG. 1 is a front perspective view of my design;

FIG. 2 is a back perspective view;

FIG. 3 is a front view;

FIG. 4 is a back view;

FIG. 5 is a left side view;

FIG. 6 is a right side view;

FIG. 7 is a top view;

FIG. 8 is a bottom view;

FIG. 9 is an enlarged view of portion 9 in FIG. 1;

FIG. 10 is an enlarged view of portion 10 in FIG. 1;

FIG. 11 is an enlarged view of portion 11 in FIG. 1; and,

FIG. 12 is an enlarged view of portion 12 in FIG. 2.

The broken line circles shown in FIGS. 1, 2, 9-12 are for showing enlarged portions that form no part of the claimed design. All other broken lines depict portions of the trash receptacle that form no part of the claimed design.

1 Claim, 12 Drawing Sheets(56)
